UNITED STATES PATENT OFFICE

JAMES P. APPLEBY, OF LOS ANGELES, CALIFORNIA, ASSIGNOR TO FRANK GRAVES
SASH, DOOR AND MILL COMPANY, OF LOS ANGELES, CALIFORNIA, A CORPORATION
OF CALIFORNIA

FRICTION SHOE FOR WINDOW SASHES

Application filed March 21, 1927. Serial No. 176,894.

This invention has to do generally with window fixtures, and is more particularly concerned with the type of fixture interposed between a window sash and its frame to exert yielding contact against one or the other for controlling the sliding movement of the sash. My invention also contemplates the combination of a window frame and sash with my improved device applied thereto.

13 The device of my invention may be used to advantage in several different situations. For instance, in my co-pending application entitled "Sash balances," filed Mar. 21, 1927, Serial No. 176,893, I have set forth a situation wherein a spring-actuated drum is applied to one side, only, of a sash. The tendency of this single balance is to rotate the sash about a horizontal axis, forcing the upper corner of the sash, at the side opposite 20 that of balance-application, into binding engagement with the frame. In that application, I have shown, and broadly claimed, means for counteracting this rotational tendency, thus insuring that the sash be held 25 squarely within the frame and therefore free to slide smoothly. The device shown in the present application is one which is adapted to function similarly to the counteracting device disclosed in said co-pending application, though it has several features which render it more capable of advantageous use 30 than the previously disclosed device.

In the above situation, the device of my invention not only counteracts the rotational 35 tendency of the sash, but also serves as a frictional retard or drag tending to hold the sash in adjusted position.

In the event it is undesirable or not feasible to use a spring actuated balance on either 40 side of the sash, I may utilize two of the devices here disclosed, one at each side of the sash.

The device is adapted to be applied to a corner of the sash, preferably, though not 45 necessarily, to an upper corner, and is so fashioned and positioned on the sash that it may be adjusted to vary the effective tension of its spring member without dismounting the sash, a feature of obvious advantage.

50 The device may be generally described as

being made up of an L-shaped member, a flat, bowed spring being applied to one of the arms and the other arm having means whereby it may be anchored to the sash. However, the details of construction and method of application may be described to better advantage in the following specification, reference being had to the accompanying drawings, in which:

55 Fig. 1 is a perspective view of a preferred embodiment of my invention;

Fig. 2 is an illustration of a sash and frame, showing my device applied thereto in a given situation;

Fig. 3 is a view similar to Fig. 2, but showing the device applied in a different situation;

Fig. 4 is an enlarged section showing my device in applied position;

Fig. 5 is a top, plan view of Fig. 4;

Fig. 6 is an enlarged fragmentary section on line 6—6 of Fig. 1; and

Fig. 7 is a detached perspective view of the pressure spring or shoe.

75 In Fig. 1 I have shown an L-shaped body or supporting member 10, the relatively short arm 11 being bent at a substantially right-angle to the relatively long arm 12. The supporting member is preferably made of comparatively stiff metal, and is of a nature 80 to be fashioned quickly and easily by punch-press operations.

Anchored to the lower end of arm 12 is a friction or pressure shoe 13 which is in the form of a flat, centrally bowed spring, the relatively straight end portions 15 and 16 contacting with the outer face 17 of arm 12. While any suitable type of anchoring connection may be utilized for holding the spring 85 to the supporting member, I have illustrated a preferred one. For this purpose I punch end 16 in a manner to provide an aperture 18 of polygonal outline. A plurality of lips 19 are pressed outwardly from arm 12, said lips being passed through aperture 18 and then turned over upon the upper face of a spring 13. In pressing out lips 20 an aperture 18a of polygonal outline is left in arm 12, and since the lips engage the defining 90 walls of polygonal aperture 18 they prevent

95

100

relative rotation of the supporting member and spring. Of course, the turned-over lip portions 20 hold the spring and supporting member against separative displacement.

5 End 15 is adapted to ride on face 17 during flexure of the spring, the arm 12 thus providing a wear-plate and assuring smooth spring action.

The under face of arm 11 preferably is 10 provided with positioning means 21. In the preferred embodiment of the invention, this means is shown to be a hollow stud which is elongated in the direction of the length of arm 11. Looking at it from another angle, 15 arm 11 may be considered as being provided with an elongated aperture 22 about which extends from the under face of arm 11 a dependent, marginal flange 23. Preferably, flange 23 is formed by pressing down the 20 stock of arm 11 during the punching of aperture 22, the flange inclining inwardly toward the axis of the aperture in order to give the stud tapered characteristics so it may more readily be driven into a window sash in the 25 manner to be described later. The described formation of flange 23 also provides a comparatively sharp edge 24 which further facilitates the entry of the stud to the sash.

The inclination of the flange also gives 30 flaring characteristics to way 25 defined by the flange, the upper, wider part of the way being of sufficient width to take a nail head, while the lower, relatively narrow portion of the way is preferably of a width just to take 35 nicely the shank of a nail or screw of given diameter.

In Fig. 2 I have indicated vertically extending window frame members 26 and 27 between which is adapted to slide sash S.

40 It may be here noted that in this figure, as well as in Figs. 3, 4 and 5, the clearance between frame and sash is greatly exaggerated in order that the structural details of my shoe may be made more clear. Frame mem-

45 ber 27 carries a spring actuated balance generally designated at 28, connection between said balance and sash S being made in the usual manner through band or tape 29. Balance 28 has a natural tendency to rotate sash

50 S about a horizontal axis in a counter clockwise direction, as viewed in Fig. 2, since the free end of the band is applied at 30 to the lower, right-hand corner of the sash. My improved shoe, generally designated at 9, is 55 therefore introduced between frame member 26 and the upper, left-hand corner 31, of sash S, said corner occurring at the junction of horizontal sash member 32 and vertical sash member 33.

60 Body member 10 is applied to corner 31 in such a manner that arm 12 lies adjacent edge 34 of member 33, and arm 11 engages the upper edge 35 of member 32. It is not necessary that the entire extent of arm 12 engage 65 face 34, though the lower end of the arm en-

gages said face when the spring is tensioned between the sash and the face 36 of member 26 which opposes face 34. With the gap or clearance G between member 26 and 33 of given extent and with balance 28 exerting a given rotative force on the sash, arm 12 is moved toward or away from member 26 to give spring 13 predetermined effective tension, the lower end of member 10 remaining in engagement with face 34 during this movement.

With the support member thus adjusted to bring spring 13 into predetermined pressural contact with face 36, arm 12 is driven down in a manner to sink or embed stud 21 in member 32 (Fig. 4), the stud thus serving to grip the sash in a manner tending to hold the support member from displacement, the elongated characteristic of the stud holding said member from rotating out of position. In order to provide a more positive anchorage for the support member, a nail or screw N may be driven through the hollow stud into the sash. The flaring characteristics of way 22 allow the head of screw or nail to be driven flush or slightly below the upper face of arm 11, though the head will contact with the inclining inner faces of flange 23 in a manner to hold the support member snugly in place.

Should it be desired to re-adjust the shoe for varying the spring tension, anchor N may be partially withdrawn (the length of the slot through which it extends rendering it easy to enter a withdrawing tool beneath its head when it is in the nature of a nail) the support member may then be lifted clear of sash member 32, and the support member swung to a new position. It then remains only to press stud 21, in its new position, back into the sash and drive the nail home again. This may all be done without dismounting the sash from its frame, a feature of obvious advantage.

When it is desired that the lower end of the support be securely anchored to the sash, a nail or similar holding device N' may be passed through aperture 18^a and into sash member 33, but this precaution is not ordinarily necessary and can only be taken when the sash is dismounted from the frame.

In Fig. 3 sash S' is mounted between frame members 26' and 27' in the manner described in connection with the sash of Fig. 2. Here, however, in place of balance 28, is shown a friction shoe 9' similar to shoe 9 and applied to the sash in the same manner. Of course, it is also possible to apply the shoes to the lower corners of the sash, and such will ordinarily be done when the sash is of considerable vertical extent, or when the clearance between frame and sash is great.

It will be evident that shoes 9, 9' not only serve to hold the sashes squarely within their frames, but also have such frictional contact

with the frame members as to tend to hold the sashes in positions to which they have been slid. In some situations, it is desirable to provide the frame members with inwardly facing sockets 39, into which springs 13 are adapted to enter to hold the sash more positively in certain given positions of adjustment, though the springs will ride out of these sockets when slight manual effort is applied

10 to the sash to raise or lower it.

It will be understood the drawings and description are to be considered merely as illustrative of and not restrictive on the broader claims appended hereto, for various changes 15 in design, structure and arrangement may be made without departing from the spirit and scope of said claims.

I claim:

1. In a device of the character described, 20 an L-shaped member, a bowed spring anchored to one of the arms of the member, and an inwardly projecting stud on the other arm, said stud being elongated in the direction of the length of said other arm.

25 2. In a device of the character described, an L-shaped member, a bowed spring anchored to one of the arms of the member, the other arm of the member having a slot extending longitudinally thereof, and a depending marginal flange about the slot.

30 3. In a device of the character described, an L-shaped member, a bowed spring anchored to one of the arms of the member, the other arm of the member having a slot extending longitudinally thereof, and a depending marginal flange about the slot, said flange inclining inwardly towards the axis 35 of the slot.

4. In a device of the character described, 40 a supporting member, a bowed spring, and means for anchoring the spring to the member, said means embodying a plurality of lips pressed outwardly from the member, through a polygonal aperture in the spring and bent 45 over the outer face of the spring, said lips engaging the defining walls of the spring-aperture.

In witness that I claim the foregoing I have hereunto subscribed my name this 21st 50 day of February, 1927.

JAMES P. APPLEBY.
